COMBINED RAILING AND WALL BRACKET

Louis Blum, Pittsburgh, Pa., assignor to Blumcraft of Pittsburgh, Pittsburgh, Pa., a firm

Filed Feb. 8, 1960, Ser. No. 59,294

Term of patent 14 years

(Cl. D13—7)

FIG. 1.

FIG. 2.

FIG. 3.

FIG. 1 is a front elevational view of a combined railing and wall bracket embodying my new design;

FIG. 2 is an end elevational view thereof; and

FIG. 3 is a cross sectional view taken along the lines and in the directions of the arrows III—III of FIG. 2.

I claim:

The ornamental design for a combined railing and wall bracket, as shown.
